UNITED STATES PATENT OFFICE.

CHARLES P. COOPER, OF NEW YORK, N. Y.

DOOR-FASTENER.

SPECIFICATION forming part of Letters Patent No. 546,064, dated September 10, 1895.

Application filed March 27, 1895. Serial No. 543,434. (No model.)

To all whom it may concern:

Be it known that I, CHARLES P. COOPER, a citizen of the United States, residing at New York, county of New York, and State of New York, have invented certain new and useful Improvements in Door-Fasteners, fully described and represented in the following specification and the accompanying drawings, forming a part of the same.

10 My invention relates to that class of door-fasteners consisting of a piece of metal or other suitable material having branches extending at an angle to each other and so arranged that when one of its branches is inserted between the margin of the door and its casing and the other branch rests upon a stationary surface in proximity to the margin of the door an incline is formed up which the door must pass in opening, and thereby 15 preventing the opening of the door so long as the fastener is in position.

The object of the invention is to provide an improved fastener of this class which shall be certain and efficient in its locking action, 20 and, further, to provide a fastener which cannot be displaced by the insertion of a thin implement between the door and casing.

A practical embodiment of my invention is represented in the accompanying drawings, 25 in which—

Figure 1 shows the fastener applied to a door as in practical use. Fig. 2 is an enlarged perspective edge view of the fastener, and Fig. 3 is a face view of the under side of fastener.

The fastener is here shown in its preferred form as formed of a flat bar of metal—steel, for example—the said bar being bent somewhat nearer one end than the other, forming 30 two branches A and A' at an angle of ninety degrees to each other, more or less. The end of the longer branch A is preferably reduced to a thin edge a, adapted to be inserted under the bottom of a door or between the free edge 35 of the door and the casing. I have shown it in Fig. 1 as in engagement with the bottom of a door B, between it and the sill C. I much prefer to form the bevel 1 for reducing the bar to the edge a on the under side of the branch 40 45 50 A, leaving the upper side of said branch

straight from the edge back toward the bend, as this construction aids greatly in preventing the displacement of the fastener from the opposite side of the door by inserting a thin implement, such as a knife-blade. I prefer, 55 also, to bevel off the side edges of the branch A for some distance from the bevel 1, these bevels 2 forming edges at opposite sides of the branch A, which afford no hold for such a thin implement, which otherwise might be 60 used to move the fastener sidewise. The branch A' of the fastener is provided with a pair of pointed legs a², conveniently formed by recessing the end of the branch A' and beveling it on its under side. When in position to fasten the pointed legs a² will rest on the sill or on the floor adjacent to the sill in such position that any attempt to open the door and slide it by the branch A will have a tendency to press the pointed legs a² into 65 the sill or floor, and thereby effectually prevent the displacement of the fastener, and the difference between the lengths of the two branches A A' being small and the angle in the neighborhood of ninety degrees the door 70 branch A will present a steep incline adjacent to the door, and will consequently prevent the door from being opened to any considerable extent. This incline may be varied somewhat and fairly good results be 75 obtained; but for the best results it should form with the floor an angle of about thirty degrees, and for good results the incline formed by the branch A with the floor when the fastener is on a level surface must be at 80 least twenty degrees. It will be understood, however, that a fastener having the bevels described forms a part of the invention whether employing this steep incline or not.

What is claimed is—

1. A door fastener having the branches A, A', the door branch A being beveled to form edge a and having side bevels 2 on its opposite edges, substantially as described.
2. A door fastener having the branches A, A', the door branch A having the bevel 1 on its under side forming edge a and a straight surface on its opposite side and having side edge bevels 2, substantially as described.
3. A door fastener having the branches A,

A', the door branch A forming an angle of at least twenty degrees with a level surface and having the bevel 1 on its under side forming edge a and a straight surface on its opposite side and having side edge bevels 2, substantially as described.

In testimony whereof I have hereunto set

my hand in the presence of two subscribing witnesses.

CHARLES P. COOPER.
